(57) **CLAIM**

The ornamental design for a monitoring device, as shown and described.

DESCRIPTION

FIG. 1 is a front perspective view of a monitoring device according to a first embodiment of the claimed design.

FIG. 2 is a rear perspective view of the monitoring device of FTG. 1.

FIG. 3 is a front view of the monitoring device of FIG. 1.

FIG. 4 is a rear view of the monitoring device of FIG. 1.

FIG. 5 is a right side view of the monitoring device of FIG. 1.

FIG. 6 is a left side view of the monitoring device of FIG. 1.

FIG. 7 is a top view of the monitoring device of FIG. 1.

FIG. 8 is a bottom view of the monitoring device of FIG. 1.

FIG. 9 is a front perspective view of a monitoring device according to a second embodiment of the claimed design.

FIG. 10 is a rear perspective view of the monitoring device of FIG. 9.

FIG. 11 is a front view of the monitoring device of FIG. 9.

FIG. 12 is a rear view of the monitoring device of FIG. 9.

FIG. 13 is a right side view of the monitoring device of FIG. 9.

FIG. 14 is a left side view of the monitoring device of FIG. 9.

FIG. 15 is a top view of the monitoring device of FIG. 9; and,

FIG. 16 is a bottom view of the monitoring device of FIG. 9.

The dash-dash broken lines in the drawings illustrate portions of the monitoring device that form no part of the claimed design.

The dash-dot-dot broken lines in the drawings represent light emission from the illumination feature of the monitoring device. The light emission forms part of the claim.
